204,649

DISPLAY RACK FOR CARPET SAMPLES

Fred Howard, New York, N.Y., assignor to Howard Self Selectors, Inc., New York, N.Y., a corporation of New York

Filed Aug. 5, 1965, Ser. No. 86,461

Term of patent 14 years

(Cl. D80—9)

FIG. 1

FIG. 2

FIGURE 1 is a front perspective view of a display rack for carpet samples showing my new design; and

FIGURE 2 is a rear perspective view thereof.

The dominant features of my design reside in the portions shown in full lines.

I claim:

The ornamental design for a display rack for carpet samples, as shown and described.

References Cited by the Examiner

UNITED STATES PATENTS

1,709,822 4/1929 Griffith ----- 211—49
3,120,826 2/1964 Bowers et al.

WALLACE A. BURKE, Primary Examiner.

JAMES R. LARGEN, Assistant Examiner.